FIG. 4

UNITED STATES PATENT OFFICE.

JOSEPH E. McGINNESS, OF PITTSBURGH, PENNSYLVANIA.

HEATING APPARATUS.

1,218,880.

Specification of Letters Patent. Patented Mar. 13, 1917.

Application filed April 8, 1916. Serial No. 89,904.

To all whom it may concern:

Be it known that I, JOSEPH E. McGINNESS, a resident of Pittsburgh, in the county of Allegheny and State of Pennsylvania, have 5 invented a new and useful Improvement in Heating Apparatus, of which the following is a specification.

This invention relates to apparatus for heating and ventilating buildings. The object of the invention is to provide apparatus which constantly renews the air in the room for purposes of ventilation and which nevertheless may be regulated to maintain an even temperature regardless of the temperature 15 of the external air. More specifically, the invention has relation to so-called indirect heating apparatus, in which a current of external air is passed over or around radiators to increase its temperature and is 20 then discharged into the room or space to be heated or ventilated.

The invention comprises the apparatus hereinafter described and more particularly pointed out in the claims.

In the drawings, which represent one embodiment of the invention, Figure 1 is a front elevation with the front wall of the casing or jacket removed to expose the interior parts; Fig. 2 is a side elevation, with 25 the side wall removed; Fig. 3 is a horizontal section on the line 3—3, Fig. 1; and Fig. 4 is a detail view, on a larger scale, and illustrating the controlling valves or dampers.

Briefly stated, my improved heating and 35 ventilating apparatus comprises a casing or jacket to be located in any suitable place in or on the walls or floors of a building and provided with communication to the air outside of said building and also to the room 40 or space to be heated and ventilated, and within which casing or jacket are located one or more radiators and an air fan or pump for circulating the air over or around the radiators into the room.

Referring to the drawings, the outer casing or jacket, indicated at 1, may be made of sheet metal or other suitable material in any desired shape or form. Intermediate 45 its top and bottom it is provided with a cross wall 2 dividing the space in said casing into a pump chamber 3 and a heating chamber 4. The bottom of the casing is closed by a floor or base 5, which may rest on a suitable support and in turn supports 50 the motor and pump.

The pump chamber 3 is provided on one side with an opening communicating with a pipe or conduit 6 having a valve or damper 7 therein and leading to the outside of the building and through which the fresh air 60 supply for ventilation is drawn. Within said chamber is a fan or pump 8, shown as a centrifugal pump, whose inlet 9 is open to the pump chamber opposite pipe 6 and whose axis coincides with the axis of the 65 pump rotor. The pump is driven by any suitable power source, such as the electric motor 10, its outlet 11 being at its top through wall 2, preferably near the center thereof, whereby the air is delivered to the 70 heating chamber 4 beneath the radiators therein.

In the heating chamber are located one or more suitable radiators 12, made up of sections banked in rows, as is usual, and separated by spaces 12a to provide free air circulation for tempering the air. Said radiator sections are connected to each other and to manifolds or supply pipes 14 for circulating or expanding the heating medium, 80 such as steam, hot water or the like therein.

Above the radiators is a cross wall 15, provided with a large number of perforations for retarding the air flow and causing the steam to spread uniformly over said 85 plate and become thoroughly mixed to temper it and produce a uniform temperature.

Above the cross wall 15 is a suitable outlet to the room, such as an arched top having a curved back 16 and whose front portion 90 opens at 17 into the room or space to be heated. The outlet 17 may, however, be in the floor, in which case no arched top is necessary, as will be readily understood. The curved back deflects the air current outwardly into the open room, and the discharge opening 17 may be protected and partially covered in any suitable manner by an ornamental grating 18, as will be readily 95 understood.

In the apparatus shown in the drawings the pump outlet 11 is located at or near the center of the heating chamber, so that it is directly beneath the radiators therein. Suitable means is provided for controlling the 105 flow of the air current through or around said radiators, so as to regulate the temperature of the air current finally discharged into the room. For this purpose the heating chamber is provided with a series of 110

dampers or valves located below the radiators and over the pump outlet 11, said dampers being arranged in two sets located respectively in a horizontal wall 19 and two vertical walls 20. Wall 19 is co-extensive with the horizontal area occupied by the radiator sections, and as the latter on both sides are spaced from the walls of the casing or shell, the edges of said wall 19 are spaced from the shell or casing. The vertical walls 20 extend downwardly from the edges of the wall 19 and upwardly along the sides of the radiators, so that open channels or spaces 21 are left between the side walls 15 of the outer casing or shell 1 and the walls 20.

In the cross wall 19 are located a series of long narrow valve plates or dampers 22, hinged at 23 and arranged somewhat like the leaves of a window shutter. Part of 20 said plates swing downwardly in one direction and part in the other, as shown. The vertical walls 20 are provided with similar dampers or plates 24. Suitable operating means is provided for operating all of said plates in unison, the arrangement being such that movement of the operating member in one direction opens the horizontal plates and closes the vertical plates, while movement in the opposite direction closes the 30 horizontal plates and opens the vertical plates. As shown, the free edges of dampers 22 are pivotally connected to rods 25, having arms 25^a rigidly connected thereto, and the free edges of dampers 24 are pivotally connected to rods 26 having arms 26^a rigidly attached thereto. Arm 25^a has solidly connected thereto an extension 25^b pivoted to a link 26^b pivotally connected to the arm 26^a. The arms 25^a are pivotally connected by links 27 to two arms 31 on a shaft 32 passing through the casing and having an operating handle 33 on its outer end. By rotating shaft 32 the links 27, 28 communicate motion to the two sets of horizontal and vertical dampers or valves, which, however, receive reverse motion, as described.

All of the air supplied by the pump 8 passes into the space beneath the walls 19 and 20 from which it issues to the open 50 space in the heating chamber. When the external air is cold, shaft 32 is turned to close the vertical dampers and open the horizontal dampers. Consequently all of the air flows directly upward through and 55 around the radiator sections, and is therefore subjected to the full heating effect of said radiators. If the outside air is warmer and does not require its temperature to be raised to such a high degree the horizontal 60 dampers are more or less closed and the vertical dampers more or less opened, so that part or all of the air flows into the channels or open spaces 21 on the outside of the radiator sections and is consequently not heat- 65 ed thereby. At the upper ends of said chan-

nels 21 are curved plates 29 which deflect the two side air currents inwardly to be mixed with the warmer air flowing past the radiators. The horizontal perforated plate 15 above the radiators chokes back the air 70 currents and distributes the air over the entire area of said plate and thoroughly mixes and tempers the air and gives it an even temperature over the entire stream. The plate 15 is preferably located a little above 75 the deflectors 29 to provide open spaces 30 therebetween through which air flows outwardly toward the side walls of the casing, as indicated by the arrows A, thereby avoiding dead air spaces above the deflectors 29. 80

By properly regulating the positions of the two sets of dampers and thereby dividing the air current to cause more or less thereof to contact with the radiator sections an even temperature may be produced irrespective of the temperature of the outside air. 85

What I claim is:

1. A unitary heating and ventilating apparatus comprising a housing having an inlet opening adjacent its bottom and a discharge opening near its top, heating radiators located at an intermediate point within said housing and arranged so that air may be forced through and over the same, said housing being provided with passages around the radiators, means within the housing arranged to draw air from the inlet opening and force it over the radiators and through the passages to the discharge opening, means for controlling the passage through and over the radiators, and means for controlling the entrance to the passages around the radiators, both of said latter controlling means being operable in unison, whereby the relative flow of air over the radiators and through the passages may be regulated. 95

2. A unitary heating and ventilating apparatus comprising a housing having an inlet opening near its bottom and a discharge opening adjacent its top, heating radiators located at an intermediate point within said housing within a passage therein, a series of horizontally located dampers controlling the entrance to said passage, said housing being provided with a plurality of passages around said radiators, a plurality of vertically located dampers for controlling the entrance to said last named passages, all of said dampers being arranged to be operated in unison, whereby the relative flow of air over and around the radiators may be regulated. 110

3. Heating and ventilating apparatus, comprising a shell or casing opening into the room or space to be heated, a pump for circulating a current of air through said casing, radiators therein, and two sets of dampers one of which controls the flow of 115 120 125 130

air between said radiators and the other of which controls the flow of air around the same.

4. Heating and ventilating apparatus, 5 comprising a shell or casing opening into the room or space to be heated, a pump for circulating a current of air through said casing, radiators therein, two sets of dampers one of which controls the flow of air 10 between said radiators and the other of which controls the flow of air around the same, and means for simultaneously operating said two sets of dampers.

5. Heating and ventilating apparatus, 15 comprising a shell or casing opening into the room or space to be heated, a pump for circulating a current of air through said casing, radiators therein, two sets of dampers one of which controls the flow of air 20 between said radiators and the other of which controls the flow of air around the

same, and a perforated wall or plate beyond said radiators for partially retarding the air flow to produce an even temperature.

6. Heating and ventilating apparatus, 25 comprising a shell or casing opening into the room or space to be heated, a pump for circulating a current of air through said casing, radiators therein, two sets of dampers one of which controls the flow of air 30 between said radiators and the other of which controls the flow of air around the same, means for simultaneously operating said two sets of dampers, and a perforated wall or plate beyond said radiators for partially retarding the air flow to produce an even temperature. 35

In testimony whereof, I have hereunto set my hand.

JOSEPH E. McGINNESS.
